United States Patent Office

Des. 193,263

Patented July 24, 1962

193,263

LIQUID SIPPING TUBE OR THE LIKE

William A. Rohlfss, 60 Crosswicks St., Bordentown, N.J.

Filed Apr. 21, 1961, Ser. No. 64,853

Term of patent 3½ years

(Cl. D2—3)

I claim:

The ornamental design for a liquid sipping tube or the like, as shown.
